UNITED STATES PATENT OFFICE.

WILLIAM S. BROWN, OF THORNTOWN, INDIANA.

BUCKLE AND TRACE-CARRIER.

SPECIFICATION forming part of Letters Patent No. 278,501, dated May 29, 1883.

Application filed March 15, 1883. (No model.)

To all whom it may concern:

Be it known that I, WILLIAM S. BROWN, a citizen of the United States of America, residing at Thorntown, in the county of Boone and State of Indiana, have invented certain new and useful Improvements in Hip-Strap Buckles and Trace-Carriers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to certain new and useful improvements in combined harness-buckles and trace-carriers; and it consists in the construction and combination of the parts, as will be hereinafter set forth, and pointed out in the claim.

In the annexed drawings, which illustrate my invention, Figure 1 is a perspective view in which the straps are shown in their relative positions, the trace-hooks being caught upon the trace-carrier. Fig. 2 is a sectional view taken through the line $x x$ of Fig. 1. Fig. 3 is a sectional view taken through the line $y y$ of Fig. 1. Fig. 4 is a plan view, showing the straps in position and the upper clamp removed. Fig. 5 is a similar view, showing the straps detached. Fig. 6 is a plan view of the upper plate.

A represents the lower portion of the buckle, which is provided at its ends with guards $a a$, under which guards is formed a passage-way or depression for the reception of the back and crupper straps. This depression is about equal to the thickness of the straps employed for the purposes. This plate A is also provided with transverse ways $c c$, which are similarly recessed or depressed. At the point, d , between the depressed portion of the plate A are provided suitable raised rims, which project slightly above the sides of the passage-ways b and c . These passage-ways a and b are provided near their central portion with upwardly-projecting pins $e e$, which are of the same height as the raised corners f , adjacent to the passage-ways b and c . This plate A is also provided at its central portion with a screw-threaded perforation, g .

The straps hereinbefore referred to are perforated at their end, so as to correspond with the projecting pins e , over which they are

placed, as shown in Fig. 4 of the annexed drawings, after which the upper plate or cover, B, is placed over the same and attached securely thereto by the screw h , which firmly unites the parts to each other and prevents the straps from being displaced or removed from the pins e . This upper plate, B, is provided at its side with extensions i , which fit within the side wall, d , of the plate A and prevent this upper plate from being turned. By means of these projecting portions i equal bearing-surfices are given to the breeching-straps at the point where they enter the buckle. The upper plate of this buckle is provided on its top, slightly rear of the center of the same, with upwardly and inwardly projecting horns or trace-carrying hooks C C. Immediately in front of the aforesaid hooks is a shield, D, which is curved rearwardly, so as to extend above and over the point of said trace-carrying hooks. This projecting plate and the trace-carrier are formed integral with the plate B, which plate is provided with a central perforation, c' , through which passes the connecting-screw h .

The shield hereinbefore referred to is for the purpose of preventing the horses' tails becoming hooked or caught in the prongs C.

The buckle and trace-carrier hereinbefore referred to rest upon the back of the horse and form a ready means for uniting the parts of the harness heretofore referred to. The same can be cheaply manufactured and ornamented to suit the different requirements of the trade, and by means of this buckle the parts of the harness can be adjusted so as to fit horses of different sizes.

Having thus described my invention, what I claim as new, and desire to secure by Letters Patent, is—

An improved trace-carrier consisting of the upper plate, B, provided with prongs C C, shield D, and side wings, $i i$, in combination with the base-plate A, having recessed ways $b c$, raised rims $d d$, and guards $a a$, substantially as described, the parts being united by a central screw, h .

In testimony whereof I affix my signature in presence of two witnesses.

WILLIAM S. BROWN.
